US00D964988S

(12) **United States Design Patent** (10) **Patent No.:** **US D964,988 S**
(45) **Date of Patent:** **** Sep. 27, 2022**

(54) **HEAD-MOUNTED DISPLAY**

(71) Applicant: **META PLATFORMS TECHNOLOGIES, LLC**, Menlo Park, CA (US)

(72) Inventors: **Quintin Morris**, Seattle, WA (US); **Peter Wesley Bristol**, Seattle, WA (US)

(73) Assignee: **META PLATFORMS TECHNOLOGIES, LLC**, Menlo Park, CA (US)

(**) Term: **15 Years**

(21) Appl. No.: **29/811,933**

(22) Filed: **Oct. 18, 2021**

(51) LOC (13) Cl. **07-05**

(52) U.S. Cl.

USPC **D14/372**

(58) **Field of Classification Search**

(57) **CLAIM**

The ornamental design for a head-mounted display, as shown and described.

DESCRIPTION

FIG. 1 is a front perspective view of a head-mounted display showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 7 Drawing Sheets
